UNITED STATES PATENT OFFICE.

EDWIN E. SLICK, OF WESTMONT BOROUGH, PENNSYLVANIA.

COMPOSITE RAIL.

1,121,677.

Specification of Letters Patent. Patented Dec. 22, 1914.

Application filed October 27, 1914. Serial No. 868,792.

To all whom it may concern:

Be it known that I, EDWIN E. SLICK, a citizen of the United States, residing in the borough of Westmont, in the county of

5 Cambria and State of Pennsylvania, whose post-office address is Johnstown, Pennsylvania, have invented certain new and useful Improvements in Composite Rails; and I do hereby declare the following to be a full, 10 clear, and exact description of the invention, such as will enable others skilled in the art to which it appertains to make and use the same.

My invention relates to improvements in 15 rails which are adapted for use on standard railways, street railways, traction lines and other tracks.

One of the essential features of my invention consists in constructing a composite 20 rail, the head or tread portion of which is of massive or compact form and outline, and is preferably made of hard and tough steel which is adapted to withstand wear and service.

25 The girder or supporting member of my rail may be made of the beam or channel type, as preferred, and of soft or medium steel, the section, depth and properties being regulated to meet the demands of the loads 30 and service to which the composite rail will be subjected.

In order to be sure of providing a safe and strong construction and one which will lend itself readily to maintenance, I prefer 35 to form the supporting member of a strength in itself sufficient to carry the loads of the rolling stock to the ties or substructure, leaving the head portion to resist the wear and friction. In certain cases, however, 40 I may figure upon the head portion and the supporting or girder member working conjointly to carry the loads, as by my manner of joining these two portions, they are made substantially as one.

45 Having thus given a general description of my invention, I will now, in order to make the matter more clear, refer to the accompanying drawings, in which like numerals represent like parts.

50 Figure 1 is a side elevation of a portion of one rail of a railway track, showing my improved construction, the bottom member in this figure being of girder or modified I-beam form. Fig. 2 is a vertical cross-section on the line II-II of Fig. 1, showing

one form of section of my construction. Fig. 3 is a view similar to Fig. 2, showing a slight variation in the conformation of the grooves in the side of the head portion, the central portion of which is curved in 60 Fig. 3 whereas it is straight in Fig. 2. Fig. 4 is a fragmentary cross-section of a portion of my composite rail head, a portion of the upper flange of the supporting girder member and showing the means for fastening 65 the head portion to the girder portion. Fig. 5 shows my construction as applied to a grooved girder rail such as is used on electric traction roads.

My construction is particularly adapted 70 for grooved girder rails especially when laid in pavements as it allows the head portion to be renewed without disturbing the other portions thus promoting ease and economy.

75 Referring now to the various characters of reference on the drawings, 1 represents a rail head of form adapted for use on standard railroads, traction railroads, or on other railroads, this being a center bearing 80 rail, 1' represents a grooved girder rail head for traction roads, 2 represents grooves formed in the sides of the heads, thereby providing small or rudimentary flanges extending laterally from the lower portions of 85 the rail heads, said flanges having surfaces 3 which are preferably somewhat inclined from the horizontal and adapted to co-operate with the fastening means for the purpose of securing the head portion and the 90 girder or base portion together.

95 4 represents a clamp bar which is originally rolled or otherwise formed to the section indicated by the full and dotted lines as clearly shown in Fig. 4, which clamp bar may be made of various lengths as or shorter than the rails, and which preferably is arranged to break joints with the same. This clamp bar is originally formed with an upwardly extending comparatively thin portion 100 5 as shown in the dotted lines and with a lower beveled or inclined side 6, adapted to fit against the correspondingly inclined inner surface of the locking flange 9. Between the clamp bar 4 and the sloping surface 3 of the rudimentary flange of the rail head I insert a wedge bar 12, the cross-section of which is in general of wedge-shaped form with the thinner edge downward; this being inserted while the upper portion of 105 110

the clamp bar is in place and of the form shown by the full lines below and the dotted lines above.

The I-beam or girder support is generally indicated at 7, which is provided with upper flanges 8 which flanges have integral upwardly extending inturned projections or locking flanges 9. The girder is also provided with the web 10 and lower base flanges 11 as shown.

The wedge bars 12 may be of the same lengths as the clamp bars 4, and may be adapted to break joints with the same, or if preferred may have their ends adjacent to the ends of said clamp bars. Splice bars for connecting the ends of the adjacent portions of my supporting member or girder portions are indicated generally in Fig. 1 of the drawing, together with the splice bolts and nuts therefor.

I prefer to form the head portions of the rails of hard tough steel, and to make the girder or supporting member of medium or structural steel, whereby the head, which is subjected to wear, will withstand such service and the lower portion which carries the weight to the substructure is well adapted to do so.

In placing my rails in position, I prefer to set the supporting ties securely and line the supporting girder members thereon in any well known manner. I then place the head portion of the rail in such a way that its base rests on the top surface of the upper flange of the girder and with one of the rudimentary flanges at the base portion of the head in close contact with the inner inclined surface of the adjacent locking flange 9, so that the sloping surface 3 is against the correspondingly inclined inner surface of the locking flange, whereby this side of the rail is held firmly and directly by the girder portion. I then place the clamp bar 4 in position, the form of this bar now being as shown by the dotted lines. In the space between the inner surface of the clamp bar and the groove in the side of the head portion of the rail, I then insert the wedge bar 12 with its narrowest portion downward, but with its lower edge a certain or considerable distance above the horizontal upper surface of the flange 8 of the girder portion. I then by the means of any suitable apparatus bend down the upwardly projecting thinner edge of the clamp bar 4 to the position shown by the full lines in Figs. 2 3 and 4. I can do this by hammering or pressing it at intervals at different locations or continuously, but prefer to perform this operation by a traversing rolling machine which exerts a rolling pressure on the outer and upper surfaces of the clamp bars and may repeat this rolling as often as necessary to secure the rail heads firmly in their positions. I may also apply this rolling

pressure to the locking flanges 9 to further make the connection very tight.

In pressing or bending downwardly the upper edge of the clamp bar 4, this drives the wedge downwardly in such a way as to clamp the head portion with a very considerable pressure within the base portion, and the wedge action of the bar 12 assists very materially in this. In doing this the wedge bar may be pushed downwardly and room is left for this purpose between the lower edge of the bar 12 and the upper surface of the top flange of the girder portion 8 as shown.

By means of my construction the lower or supporting member is maintained in position in the road-bed and none of its flanges nor other portions need be bent nor disturbed in any manner in order to place a new or remove a wornout rail head.

The clamp bars may be made of medium or of comparatively soft steel which will allow them to be bent readily to the forms desired and this is accomplished more easily, economically and surely than to attempt to bend over rail flanges or other portions of very hard steel, or to attempt to bend integral portions of the head or base members of the compound rail. I may, however, make the clamp bars of hard steel of high elastic limit, in which case, they may be of lighter sections, if desirable.

Although I have shown and described my improvements in considerable detail, I do not wish to be limited to the exact and specific details shown and described, but may use such substitutes, modifications or equivalents thereof, as are embraced within the scope of my invention, or as pointed out in the claims.

Having thus described my invention, what I claim and desire to secure by Letters Patent is:

1. A compound rail comprising a head portion, a base portion provided with a locking flange, a clamping bar adapted to be held by said locking flange, a bar of wedge section between the clamp bar and the head portion, a portion of said clamping bar being bent into contact with said wedge bar.

2. A compound rail comprising a head portion, a base portion provided with integral locking flanges on the edges thereof, a clamping bar, adapted to be held by one of said locking flanges, a bar of wedge section between the clamp bar and the head portion, a portion of said clamping bar being bent into contact with said wedge bar.

3. A compound rail comprising a head portion with small flanges on the sides thereof, a base portion provided with integral locking flanges on the edges thereof, one of said locking flanges extending over one of the head flanges aforesaid, a clamping bar adapted to be held by the other lock-

ing flange, a wedge bar between the clamp bar and one of the head flanges, a part of said clamping bar being bent over the wedge bar.

- 5 4. A compound rail comprising a compact head portion, comparatively small integral flanges on the lower edges thereof, a base portion provided with integral locking flanges, a clamping bar adapted to be held 10 by one of said locking flanges, a wedge bar between the clamping bar and one of the head flanges, said clamping bar being bent into contact with the wedge bar.

5. A compound rail comprising a head 15 portion, comparatively small flanges on the lower edges thereof, a girder base portion, the upper flanges of which are provided with integral locking flanges, a clamping bar adapted to be held by one of said locking 20 flanges, a wedge bar between the clamping bar and one of the head flanges, a portion of said clamping bar being bent into contact with the wedge bar.

6. A compound rail comprising a compact 25 head portion with longitudinally grooved sides forming small flanges on the lower edges thereof, a girder base portion, the edges of the upper flanges of which project upwardly and inwardly forming integral 30 locking flanges, a clamping bar adapted to be held by one of said locking flanges and bent into contact with a wedge bar which is located between the clamping bar and one of the head flanges.

- 35 7. A compound rail comprising a compact head portion provided with small flanges on the lower edges thereof, a girder base portion provided with upper flanges, the edges of which are turned upwardly and inwardly, 40 thereby forming integral locking flanges, a clamping bar, provided with an inclined side adapted to fit under one of said locking flanges, a wedge bar between the clamping bar and the head portion, the upper 45 portion of said clamping bar being bent into contact with the wedge bar.

8. A compound rail comprising a compact head portion provided with small flanges on the lower edges thereof, a girder base portion provided with upper flanges the edges of which are turned upwardly and inwardly, thereby forming integral locking flanges, a clamping bar provided with an inclined side adapted to fit under one of said locking 55 flanges, a wedge bar between the clamping bar and the head portion, the upper portion of said clamping bar being bent into contact with said wedge bar.

9. A compound rail comprising a compact 60 head portion of hard tough material, provided with comparatively small flanges on the lower side edges thereof, a girder base portion of softer material provided with

upper flanges, the edges of which are upwardly and inwardly turned, thereby forming locking flanges, the portion between said locking flanges being adapted to serve as a seat for the rail head, a clamping bar, portions of which are adapted to fit under and to be held by one of said locking flanges, 70 a wedge bar between the clamping bar and the other flange of the head portion, the upper part of said clamping bar being bent into contact with the wedge bar.

10. A compound rail comprising a head 75 portion of hard material, a girder base portion of softer material, said base portion being provided with a locking flange formed integral therewith, a clamping bar adapted to be held by said locking flange, a wedge 80 bar between the clamping bar and the head portion, a portion of said clamping bar being bent into contact with said wedge bar.

11. A compound rail comprising a compact head portion provided with a flat bottom and rudimentary flanges extending laterally of the lower edges thereof, a girder base portion the edges of the upper flanges of which are upwardly and inwardly turned forming locking members, the portion of 90 said upper flange between the locking members being adapted to provide a rail seat, a clamping bar, the lower portion of which is adapted to fit under one of said locking members, a wedge bar between said clamping bar and the head portion, the upper portion of said clamping bar being bent 95 into contact with the wedge bar aforesaid.

12. A compound rail comprising a head portion, a base portion provided with an 100 inwardly turned locking flange, a clamping bar of comparatively small cross-section adapted to be held by said locking flange, a wedge bar between said clamping bar and head portion, a portion of said clamping 105 bar being bent into contact with said wedge bar.

13. A compound rail comprising a head portion, comparatively small lateral flanges on the lower edges thereof, a girder base 110 portion the edges of the flange of which are upwardly and inwardly turned, thereby forming flanges, a clamping bar of comparatively small section adapted to be held by one of said locking flanges, a wedge bar 115 between said clamping bar and head portion, a portion of said clamping bar being bent into contact with the wider edges of the wedge bar aforesaid.

In testimony whereof I hereto affix my 120 signature in the presence of two witnesses.

EDWIN E. SLICK.
